(57) CLAIM

The ornamental design for a leg mounted mouse pad with integrated mouse holster, as shown.

DESCRIPTION

FIG. 1 is a perspective view of the leg mounted mouse pad with integrated mouse holster of my new design;

FIG. 2 is another perspective view thereof;

FIG. 3 is a top view thereof;

FIG. 4 is a right view thereof;

FIG. 5 is a bottom view thereof;

FIG. 6 is a front view thereof;

FIG. 7 is an enlarged back view thereof; and,

FIG. 8 is back view thereof.
